CLAIM

The ornamental design for a combined tractor cab and hood, as shown and described.

DESCRIPTION

FIG. 1 is a right front perspective view of a combined tractor cab and hood embodying my new design, it being understood that the broken lines are for illustrative purposes only;

FIG. 2 is a left side elevational view thereof;

FIG. 3 is a top plan view thereof;

FIG. 4 is a front elevational view thereof; and

FIG. 5 is a rear elevational view thereof.
